Primary Examiner — Carla J Wright(74) *Attorney, Agent, or Firm* — Dinsmore & Shohl LLP(57) **CLAIM**

The ornamental design for a SLEEVE FOR ELECTRONIC DEVICE as shown and described.

DESCRIPTION

FIG. 1 is a perspective view including the front, top, and side of a sleeve for electronic Device showing our new design;

FIG. 2 is a perspective view including the rear, top, and side of the sleeve for electronic device of FIG. 1;

FIG. 3 is a front elevation view of the sleeve for electronic device of FIG. 1;

FIG. 4 is a rear elevation view of the sleeve for electronic device of FIG. 1;

FIG. 5 is a side elevation of the sleeve for electronic device of FIG. 1;

FIG. 6 is an opposite side elevation view of the sleeve for electronic device of FIG. 1;

FIG. 7 is a top plan view of the sleeve for electronic device of FIG. 1; and

FIG. 8 is a bottom plan view of the sleeve for electronic device of FIG. 1.
